UNITED STATES PATENT OFFICE

2,637,159

CHAINMAKING APPARATUS

Robert L. Cooke, Attleboro, Mass., assignor to
Charles D. J. Smith, Attleboro, Mass.

Application January 27, 1950, Serial No. 140,829

4 Claims. (Cl. 59—10)

1

This invention relates to a chain making apparatus of the type wherein a solid bar of stock is rolled to provide a chain.

Heretofore, in an apparatus of the above general type, difficulty has been experienced in keeping the edges of the rolls which engage the stock from contacting one another and becoming broken. Also, difficulty has been provided in the separation of the links by cutting through the stock and severing it. Also, it has been experienced that due to the terrific pressures developed in the machine, that only very soft stock could be handled.

One of the objects of this invention is to provide a machine having two pairs of opposed rolls which will be so arranged that the rolls while being maintained against the terrific pressures developed will not be permitted to contact each other so as to destroy the cutting edges or faces of the rolls.

Another object of this invention is to provide fins or cutters which will completely sever the stock into the individual links to be provided as the stock passes through the rolls.

With these and other objects in view, the invention consists of certain novel features of construction, as will be more fully described and particularly pointed out in the appended claims.

In the accompanying drawings:

Figure 1 is a top plan view of the machine which is constructed in accordance with this invention;

Figure 2 is a side elevation of the apparatus;

Figure 3 is a fragmental view on a much larger scale showing in elevation one of the rolls;

Figure 4 is a top or edge view of the structure shown in Figure 3;

Figure 5 is a sectional view taken substantially upon the axes of the four rolls and showing the fragmental portion of each of the rolls in its mitered relation with a piece of stock in operating position;

Figure 6 is a plan view of a piece of work produced;

Figure 7 is a plan view of a modified piece of work.

In proceeding with this invention, I provide two opposite pairs of rolls arranged at right angles to each other with their axes in substantially the same plane. Bevelled gears are provided to cause the rolls to rotate in unison, one of the rolls being driven by a suitable shaft. The rolls are provided with depressions on their circumferential surfaces which follow the exterior form of the chain to be produced, there being fins to divide the links as a solid bar of stock is rolled between

2

them. Each of these rolls is provided with a mitered circumference so that the group may be meshed together and in order that the rolls of one pair will not contact, shoulders are provided on each pair of rolls to engage an annular face of the other pair of rolls. Thus, each pair of rolls serves as a stop to prevent the other pair of rolls from engaging, and in this way although terrific pressures are encountered and resisted, the rolls never can engage so as to destroy their working circumferential surfaces.

With reference to the drawings, 10 designates generally a frame having a bed plate 11 upon which is rotatably supported in suitable bearings 12 and 13 a pair of rolls 14, 15, the roll 14 being mounted upon a shaft 16 and the roll 15 being mounted upon a shaft 17, which latter extends out from the frame to act as a drive shaft for the machine. Bearings 18 and 19 serve to mount shafts 20 and 21 upon which there are rolls 22 and 23 as another pair of opposed rolls located at right angles to the rolls 14 and 15. Bevel gears 24 and 25 secured to the roll 15 serve to drive bevel gears 26 and 27 secured to the rolls 22 and 23, while bevel gears 28 and 29 on the opposite sides of these rolls mesh with the bevel gears 30 and 31 on the roll 14 and drive this roll so that as the shaft 17 rotates, all of the rolls rotate in unison with a balanced drive.

The rolls as shown in greater detail at their meshing portions in Figure 5 have mitered portions 30 and 31 in opposed relation on the rolls 14 and 15, and 32 and 33 in opposed relation on the rolls 22 and 23. The circumferential bevelled edges of each of the rolls is substantially identical and comprises depressions 34 (Figs. 3 and 4) which follow the exterior form of the chain to be produced, while between these depressions 34 there are fins 35 which serve as cutters to cut through a bar of stock as it passes between the rolls. These fins 35 have their faces in substantially the bevelled surface 36 of the roll, while adjacent this fin the stock is cut away as at 37 and yet is not of the depth of the depression 34 which forms the exterior surface of the chain. The fin 35 on the opposite bevelled surface may be seen as at 35' in Figure 3 with its cooperating cutaway portion 37' at either side thereof. We thus have a duplicate of the depressions and fins on each of the mitered or bevelled surfaces of each of the rolls, the arrangement being such that the depressions 34 on one face are staggered with reference to the depressions 34' on the opposite face, as can well be seen in Figure 4.

The formation of the depressions and fins,

as can readily be seen, presents a very delicate and sharp edged arrangement and one which could readily be injured, should opposed pairs of rolls come in contact.

In order to prevent the rolls from moving toward each other into contact, the rolls 14 and 15 are provided with shoulders 40 so as to engage the annular face 41 of the washers 42 on either side of the rolls 22 and 23. Also, shoulders 43 are provided by the washers 42 so as to engage the annular faces 44 of the rolls 14 and 15.

By providing four rolls with their mitered surfaces in close adjacency, a bar of stock usually in the form of a cross in cross section may be fed between these rolls and will emerge in link form. The links will be of an ornamental shape depending upon the depressions and the ability of the fins to cut between the links or in some cases to sever the stock from the links sufficiently close to the depressions which have been formed so that the link formation may be had.

The chain shown in Figure 6 is severed as at 45 leaving links of generally rectangular form. The shape of a wire chain 46 is provided with webs 47 extending therefrom. In some cases a modification may be provided by forming the edges of the recesses 34 into cutting fins and producing a chain of the wire form as shown at 48 in Figure 7.

I claim:

1. In a chain making apparatus, two pairs of opposed symmetrically located rolls arranged at right angles to each other with their edges mitered at equal angles to fit together, said rolls being provided with depressions on their circumferential surfaces which follow the exterior form of the chain to be produced, and each of said

opposed pairs of rolls having shoulders at right angles to the axis and each of said opposed pairs having annular faces parallel to the axes presented to the shoulders of the other set of opposed pairs of rolls to limit the movement of the axes of each pair of rolls toward each other so that the work forming edges may not interfere.

2. In a chain making apparatus as in claim 1 wherein the miters of one pair of rolls have their shoulders extending outwardly from the base of the miter.

3. In a chain making apparatus as in claim 1 wherein the miters of one pair of rolls have their annular faces extending inwardly toward their axes from the base of the miter.

4. In a chain making apparatus as in claim 1 wherein the miters of one pair of rolls have their shoulders extending outwardly from the base of the miter and the other set of rolls have their annular faces to engage therewith extending from the base of their miter.

ROBERT L. COOKE.
